UNITED STATES PATENT OFFICE.

ALFRED SHEDLOCK, OF JERSEY CITY, NEW JERSEY, ASSIGNOR TO I. B. KLEINERT RUBBER COMPANY, OF NEW YORK, N. Y., A CORPORATION OF WEST VIRGINIA.

CLASP.

No. 829,176.

Specification of Letters Patent.

Patented Aug. 21, 1906.

Application filed March 24, 1906. Serial No. 307,769.

To all whom it may concern:

Be it known that I, ALFRED SHEDLOCK, a citizen of the United States, and a resident of Jersey City, Hudson county, State of New Jersey, have invented Improvements in Clasps, of which the following is a specification.

The kind of a clasp to which this invention relates comprises an open-face member having downwardly-converging sides and a block or solid member having downwardly-converging grooves formed in its sides adapted to coact with the converging sides of the other member to clasp a fabric between them, the grip on which increases with an increase of strain applied to the fabric.

This invention relates particularly to the two members of the clasp, as will hereinafter be fully described by reference had to the drawings accompanying this specification, in which—

Figure 1 is a front elevation of a clasp embodying the present improvements. Fig. 2 is a longitudinal vertical section taken on the line 2 2, Fig. 1. Fig. 3 is a rear view of the interior member or button of the clasp. Fig. 4 illustrates the manner of preparing the button-cord before it is secured to the button. Fig. 5 is a view of the loop detached; and Fig. 6 is a transverse section of the same, taken on the line 6 6, Fig. 5.

One of the features of this invention is the manner of constructing the interior member or button of the clasp and attaching thereto its suspension and connecting cord. This button is in the form of a block with the base *a* substantially rectangular and the front portion *b* formed with its lower end rounded and having side grooves *c* converging downwardly and somewhat smaller than the base *a*. It is designed to be molded to shape of any suitable plastic material, celluloid being preferred, and as much as possible of the interior is provided with spaces extending from the under side by suitable cores in the mold to save material of which the button is made. The suspension-cord *d*, molded in the button, as shown in the main view of the drawings, is formed into a loop with the ends secured together, as by a metal clamp-sleeve *e*, Fig. 4. It is held in the mold by the connected part *e* resting against the core which forms the space or recess *f*, the material

forming around the lower part of the cord *d*, and the connection *e* as the button is made in the mold. Economy of manufacture is had by this method of making clasp-buttons of this character, and an effective button is produced, either plain or ornamental, as desired. The other member of the clasp is a loop having converging sides, the space between them being narrower at the lower than at the upper part, which upper part is large enough for the front *b* of the button to pass through in the flat position, but narrow enough to prevent the base *a* passing through it, the lower inside portion of the loop being adapted to receive the inclined grooves *c* of the button and to coact therewith to grasp and hold a fabric extending over the face or front of the button. This loop is composed of a moldable material *g*, similar to the button, formed around a metal core *h*. This core, which will take most of the strain imparted to the loop, is preferably made of spring-wire bent at the middle, with upwardly-extending branches, which are straight throughout their length, with their ends bent toward one another to constitute the holding-bar *i* of the loop, as shown at Fig. 5. The covering material *g* surrounds the whole of the U-shaped portion of the loop and is by a suitable mold formed cylindrical at the portions *j* on the upper parts of the sides of the wire core *h* and is oval or egg shape in cross-section at the lower parts of the sides and the bend of the loop, the small end of oval extending inwardly to form an internal flange *k*, which is thinner than the other portions of the loop, with the opposing faces of its two sides at an angle to one another corresponding to the angle of the grooves *c* of the button, as clearly shown at Figs. 5 and 6. The object of thus forming the loop is to enable the clasp to be made as thin as possible while providing coacting gripping-surfaces of sufficient width or bluntness not to injure the fabric gripped and making the other parts of the loop large enough with sufficient strength to withstand all working strains. In applying a button of this character provided with a suspension-cord and a loop to practical use the bar *i* of the loop and the cord *d* of the button are connected together and to the band or webbing of the supporter, such a connection being shown at Fig. 4, to the end of a piece of web-

bing *l*, which is passed around the bar *i* and cord *d* and secured above them by sewing, as shown at Figs. 1 and 2.

It will be understood that the button here described may be used with loops of other make than the one shown and that loops of this special construction may be used with other styles of buttons—as, for instance, the button shown and described in the application filed March 24, 1906, for improvements in clasps under Serial No. 307,768, and which consists of moldable material formed around a hollow metal core and having inclined grooved sides, said core being provided with lugs extending beyond the bottom of the button, and a plate provided with perforations through which the lugs of the core pass and are bent over or riveted after passing through a fabric located between the button and the plate.

The principle of operation involved is that described in the Letters Patent No. 594,568, issued to me November 30, 1897, for improvements in clasps, in which the loop has the lower portions of its sides convergent to coact with the gripping-faces of a button and with the space between the upper portions of the sides wide enough for the admission of a button to the loop to locate the button in operative position in plane therewith.

I claim as my invention—

1. In a clasp, in combination, a loop consisting of a metal core having straight sides and a moldable material surrounding the same, the inner faces of the lower part of the loop formed by the moldable material being straight and downwardly convergent and the space formed thereby being of less width than the space at the upper part of the loop; and a button having inclined grooves at its sides to coöperate with the lower part of the loop to grip a fabric, and provided with suspension means attached to the top of the loop.

2. In a clasp, a button-gripping member formed of moldable material having grooved sides; in combination with a suspension-cord the ends of which are permanently secured to the button by being molded therein and the main portion thereof extending from the top of the button.

3. In a clasp, a button-gripping member formed of moldable material having grooved sides and openings formed in its rear surface; in combination with a suspension-cord the

ends of which are fastened together and are permanently secured to the button by being molded therein and the main portion thereof extending from the top of the button.

4. In a clasp, a loop consisting of a metal core formed with straight sides, a bend at the lower end and a sustaining-bar at the upper end, in combination with a covering of a moldable material formed to surround the upper parts of the sides of the core with uniformity and the lower portion of the loop with a flange internally arranged, whereby the loop-opening is wider at its upper than at its lower part and the faces of the lower part converge downwardly.

5. In a clasp, a loop consisting of a metal core formed with straight sides, a bend at the lower end and a sustaining-bar at the upper end, in combination with a covering of a moldable material formed to surround the upper parts of the sides of the core with uniformity and the lower portion of the loop with a flange of reduced width internally arranged, whereby the loop-opening is wider at its upper than at its lower part and the faces of the lower part converge downwardly; in combination with a flat button the face portion of which is adapted to pass through the wide upper part of the loop-opening and provided with side grooves to coact with the flange of the lower part of the loop-opening; and means for attaching the top of the button and loop together.

6. In a clasp, a button-gripping member formed of moldable material having grooved sides; in combination with a suspension-cord the ends of which are permanently secured to the button by being molded therein and the main portion thereof extending from the top of the button; in combination with a loop comprising a metal core and a covering of moldable material formed with a flange extending inwardly at the lower part of the loop to constitute coacting gripping-surfaces with the grooves of the button; and means connecting the cord of the button to the top bar of the loop.

In testimony whereof I have hereunto subscribed my name this 22d day of March, 1906.

ALFRED SHEDLOCK.

In presence of—

J. C. MCKIBBIN,
JAMES A. HUDSON.
